(57) **CLAIM**

The ornamental design for a palm leaf dinnerware plate, as shown and described.

DESCRIPTION

FIG. 1 is an isometric view of a palm leaf dinnerware plate according to the present disclosure;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The palm leaf dinnerware plate is made from a compressed palm leaf material and accordingly has the texture and pattern of a compressed palm leaf.
